(57) **CLAIM**

The ornamental design for a twin baby bath, as shown and described.

DESCRIPTION

FIG. 1 is a front isometric view of a twin baby bath showing the design.

FIG. 2 is a front plan view thereof.

FIG. 3 is a rear plan view thereof.

FIG. 4 is a left side elevation view thereof.

FIG. 5 is a right side elevation view thereof.

FIG. 6 is a top plan view thereof; and,

FIG. 7 is a bottom plan view thereof.

The dashed lines shown in the drawings indicate portions of the design that are not presently claimed and thus form no part of the claimed design.

1 Claim, 7 Drawing Sheets
